UNITED STATES PATENT OFFICE.

CHRISTIAN F. LAUN, OF WATERVILLE, CONNECTICUT, ASSIGNOR TO BERBECKER & ROWLAND MANUFACTURING COMPANY, OF WATERVILLE, CONNECTICUT, A CORPORATION OF CONNECTICUT.

BRACKET.

956,983.

Specification of Letters Patent.

Patented May 3, 1910.

Application filed November 4, 1909. Serial No. 526,162.

To all whom it may concern:

Be it known that I, CHRISTIAN F. LAUN, a citizen of the United States, and a resident of Waterville, in the county of New Haven 5 and State of Connecticut, have made and invented certain new and useful Improvements in Brackets, of which the following is a specification.

My invention relates to an improvement in 10 brackets, and more particularly to such as are employed for use in connection with curtain poles, rods, or the like, the object being to provide a bracket which will be cheap and economical to construct, neat in appearance, 15 and with which the rod or pole may be easily and readily assembled.

A further object of my invention is to provide a bracket which will effectually hold 20 the ends of the curtain pole in engagement therewith, and without danger of their becoming accidentally disengaged.

A further object of my invention is to so construct the bracket that it may be used either as an outside or inside bracket, and 25 either on the right or left hand side of a door jamb, window frame, etc., and with these and other ends in view, consists in certain novel features of construction and combinations of parts, as will be hereinafter fully 30 described and specifically pointed out in the claims.

In the accompanying drawings, Figure 1 is a view in elevation of my improved bracket having an extension curtain rod engaged or 35 assembled therewith, the brackets being shown as outside brackets. Fig. 2 is a view showing the brackets in use as inside brackets. Fig. 3 is a sectional view of the bracket and one end of the curtain pole assembled 40 therewith. Fig. 4 is a detached view in perspective of the bracket.

Referring to the drawings, 5 represents a window frame, door jamb, or the like, to which the brackets and pole are secured, 6 45 representing a telescopic rod or curtain pole provided on each of its ends with a ferrule 7 formed with the ball or knob 8, and having openings 9—10 formed in a vertical line for the reception of the spring arm of the 50 bracket. Each of these brackets comprises a plate 11 formed with the openings 12 for the reception of retaining nails or screws 13 for securing it to the window frame 5. The

bracket about midway its length is bent to form the horizontal plate 14 and then into 55 the vertical arm 15, this latter arm formed by bending the metal over and upon itself forming the spring fingers or sections 16, 17, the extreme lower end of the spring finger 17 being turned inwardly as illustrated at 18 60 to prevent its catching or engaging the ball or knob 8.

Near the lower end of the arm 15, the metal of the spring fingers 16—17 is bent outwardly to form the retaining spherical 65 shaped ball or knob 19 which when the parts are assembled as illustrated in the sectional view (Fig. 3), fits within the hollow ball 8 to retain the parts in their assembled position. 70

It will be noted by reference to Figs. 1 and 2 that the bracket may be used either as an outside or inside bracket, and either on the right or left hand side of the window frame; furthermore, that in assembling the 75 rod with the brackets, the arm 15 projects upwardly through the openings 9, 10, the sides of these openings causing the sections 16, 17, to close or approach each other, and to again separate after the ball or knob 8 80 has passed over and beyond the retaining enlargement 19. This projection or enlargement, fitting within the ball or knob 8, is hidden thereby, and thus in no way detracts from the appearance of the article. Furthermore, it effectually locks the several parts 85 in their proper relative positions and avoids any and all danger of the pole becoming accidentally disengaged from the bracket.

Having fully described my invention, what 90 I claim as new and desire to secure by Letters Patent, is:

1. A bracket for use in connection with a curtain pole, comprising a vertical plate for attachment of the bracket in place, said 95 plate being bent at right angles and then into a vertical arm, said arm being formed by bending the metal over upon itself and provided near its lower end with a spherical retaining projection, substantially as described.

2. The combination with a curtain pole provided on each end with a ball having 100 openings therein, of brackets each comprising a vertical attaching plate bent at right angles into a horizontal plate and then into

a vertical arm, said arm being formed by bending the metal over and upon itself and provided near its lower end with a retaining spherical projection adapted when the parts 5 are assembled, to be contained within the ball on the end of said pole, substantially as described.

Signed at Waterville, in the county of New Haven, and State of Connecticut, this 1st day of Nov. A. D. 1909.

CHRISTIAN F. LAUN.
